The drawing shows a vertical assembly of four vertical bars. The top two bars are connected by a horizontal bar labeled '10'. The bottom two bars are connected by a horizontal bar labeled '38'. A central vertical bar labeled '12' is positioned between the two pairs. A horizontal bar labeled '39' connects the bottom of bar '12' to the bottom of bar '38'. A circular component labeled '34' is attached to the right side of bar '12'. The entire assembly is labeled 'Fig. 12' in the top right corner.

UNITED STATES PATENT OFFICE.

WILLIAM J. MILLER, OF LOGANSPORT, INDIANA, ASSIGNOR OF ONE-THIRD TO GEORGE E. CREED, OF LOGANSPORT, INDIANA.

NAILING MACHINE.

Application filed September 14, 1925. Serial No. 56,237.

This invention relates to machines for driving nails, and has for one of its objects to improve the construction and increase the efficiency and utility of devices of this character.

Another object of the invention is to provide a device of this character in which a plurality of nails may be simultaneously driven.

Another object of the invention is to provide a device of this character operative by compressed air and in which the nails are individually and consecutively set in position and held in the path of the driving elements.

With these and other objects in view the invention consists in certain novel features of construction as hereinafter shown and described and then specifically pointed out in the claims, and in the drawings illustrative of the preferred embodiment of the invention.

Figure 1 is a front elevation of the improved device, partly in section.

Figure 2 is a side elevation.

Figure 3 is a plan view, with the compressed air supply tube in section.

Figure 4 is a section on the line 4—4 of Figure 1.

Figure 5 is an end elevation enlarged, of one form of the nail trap, from the discharge end.

Figure 6 is a section on the line 6—6 of Figure 5.

Figure 7 is an end elevation of the form of nail trap shown in Figure 5, from the operative end.

Figure 8 is a plan view of the nail trap shown in Figures 5, 6 and 7 with the nail conductor in section on the line 8—8 of Figure 5.

Figure 9 is a vertical sectional detail, illustrating the construction and operation of plunger devices.

Figure 10 is an enlarged sectional detail of the device for holding the nail in the path of the driving plunger.

Figure 11 is a transverse section on the line 11—11 of Figure 10.

Figure 12 is a transverse section on the line 12—12 of Figure 9.

Figure 13 is a detail illustrating a modification in the construction of the nail trap, and partly in section.

Figure 14 is a side view of the parts shown in Figure 13.

Figure 15 is a plan view, partly in section, of the modified structure shown in Figures 13 and 14.

Figure 16 is a detached perspective view of the nail shifting plate shown in the modified trap structure.

Figure 17 is a sectional detail of another modified construction of the nail trap.

Figure 18 is a side elevation of the parts shown in Figure 17.

The improved device in the form shown in Figures 1, 2 and 9, includes a supporting base 10 secured by any suitable means to a support, for instance, by a bracket 11.

Rigidly secured at their lower ends in the base 10 are spaced guide rods 12 and 13, the latter coupled at their upper ends by an outwardly curving cross head 14.

Slidably engaging the rods 12 and 13 by bearings 15 and 16 is a guide member 17, with an intermediate half bearing 18 and cap 19 to receive a cylindrical member 20 into which the compressed air is conducted. Extending into the cylinder 20 is a tubular member 21 to the upper end of which the air hose 21¹ is attached.

The bearings 15 and 16 are provided respectively with guide lugs 22 and 23 to receive nail trap operating rods 24 and 25.

Coiled springs 26 and 27, respectively, surround the guide rods 12 and 13 between the bearings 15 and 16 and the base plate 10, while coiled springs 28 and 29, respectively, surround the trap rods 24 and 25 between the guide lugs 22 and 23 and the cross head 14.

The rods 24 and 25 are provided respectively with stop nuts 30 and 31 above the lugs 22 and 23, and the rods extend loosely through the cross head 14 and terminate in lateral heads 32 and 33, as shown, the object thereof to be hereinafter explained.

Coacting plungers 34 and 35 are connected at their upper ends to a head member 36, and extending from the latter and into the cylindrical member 20, is a stud 37 to enable cylinder 20 and head 36 to be coupled. Depending from the base 10 are tubular guide members 38 and 39 for the plungers 34 and 35.

The receptacle for the nails to be driven is represented as a whole at 40, and is di-

vided by a central partition 41 into two compartments.

Supported by any suitable means, for instance, by brackets 41 and 42 from the base 5 10, are nail guide chutes or conductors 43 and 44, one for each of the guide tubes 38 and 39, and communicating with the lower portions of the same.

Supported respectively upon the nail chutes 43 and 44 are nail trap devices, and as they are alike except that they are rights and lefts, the description of one will suffice for both.

The nail trap devices disclosed in Figures 15 1 to 8 comprise a cylindrical casing 45, open at one end and in which a cylindrical body 46 is mounted for rotation and provided with a stub shaft 47 extending through the closed end of the casing, the body 46 being 20 formed with a plurality of outwardly opening nail receiving sockets 48.

Extending between each of the casings 45 and the nail holding member 40 are guide chutes 49 and 50, each chute opening inwardly or toward each other and closed at their outer edges, and the closed portions laterally enlarged as at 51 and 52 to receive the heads of the nails.

The container 40 is formed with passages 30 at each side of the partition 41, and indicated at 53 and 54 in Figure 3, the chute 49 communicating with the passage 53 and the chute 50 communicating with the passage 54.

The casings 45 are each formed with 35 longitudinal passages 55 registering with the chutes 49 and 50.

The nails are disposed in the compartments formed by the partition 41 with the heads in the compartment at the left all in 40 one direction and adapted to consecutively enter the chute 49 with the heads adapted to engage in the enlargement 51, while the nails in the compartment at the right are arranged with their heads all in the opposite 45 direction and adapted to enter the chute 50 with the heads adapted to engage in the enlargement 52.

The sockets 48 are adapted to consecutively register with the slots or passages 55 50 of the casing as the member 46 is intermittently rotated.

Mounted on each of the stub shafts 47 is 55 a ratchet device 56 having teeth 57 corresponding to the sockets 48.

Mounted to rotate on a collar on each of the ratchets 56 is a lever arm 58 to which the lower ends of the rods 24 and 25 are pivoted as shown. The lever arms are provided respectively with pawls 59 to engage the ratchet teeth.

Disposed in each of the chute devices 43 and 44 is a small stop, one of which is shown at 60, upon which the heads of the nails are caught as they fall from the socketed member 46, and the head ends held back while

the pointed ends are carried down by gravity through the chutes 43 and 44 and automatically disposed in vertical position and thus conducted into the lower part of the members 38 and 39 and into the paths of the 70 plungers 34 and 35.

At their lower ends each of the members 38 and 39 is provided with a bearing disk 61, and formed in the opposite sides of the members 38 and 39 are longitudinal slots 75 62. Pivoted at 63 in each slot are opposing nail supporting bars 64, the bars being spring supported at their lower ends as shown at 65 in Figures 10 and 11, and thus normally maintained yieldably in relatively 80 close relations at their lower ends. The confronting faces of the bars 64 are formed with longitudinally directed sockets 66 in their lower portions, as shown, to receive the lower or point portions of the nails, the bars 85 operative to automatically hold the nails in position in the path of the plungers while being driven.

In preparing the device for operation, the holder 40 is supplied with nails arranged 90 with their heads pointing in opposite directions in the two compartments, as before described, the nails in one compartment passing consecutively down the chutes 49 and 50 until the latter are filled, with the lowermost 95 nails in the sockets 48 of the members 46 which for the time being are uppermost. The device is disposed upon the material through which the nails are to be driven, indicated conventionally at 67. Compressed 100 air is then admitted to the cylinder through the tube 21 and forces the cylinder and plungers 34 and 35 downwardly.

The travel of the plunger is relatively long and the travel of the member 17 corresponds thereto, and at the first downward portion of the stroke, the lugs 22 and 23 moving with the member 17 releases the springs 28 and 29 which by their reaction press against the stop nuts 30 and 31 and move the trap rods 24 and 25 downward and cause them to actuate the arms 58 and set the pawls 59 over one of the teeth 57, ready to actuate the nail trip at the return stroke.

One nail is at all times disposed in the socket 48 which for the time being is uppermost, and another nail in the socket which for the time being is in the half-way located socket, and when the trap rods are actuated as above described, the nails which for the time being are in the half-way or intermediate position will be carried around and dropped into the chutes 43 and 44 and turned into vertical position by the stops 60 and deposited in the lower portions 110 of the guide tubes 38 and 39 and into the paths of the descending plungers, and held in true vertical position by the coaction of the bars 64.

When the plungers 34 and 35 have reached 115

the limit of their downward stroke, or have driven the nails fully into the members 67, the compressed air will be shut off, when the reaction of the springs 26, 27, 28 and 29, 5 will restore the parts to normal position ready for the next operation.

After the nails are driven, the device will be moved to position for the next drive, and so on as required.

10 The improved device is simple in construction, can be inexpensively manufactured, of any required size, and adapted to drive nails of various sizes and lengths.

In Figures 13 to 16 is shown a modified 15 construction of the trap device, consisting in substituting for the cylindrical member 45 and socketed member 46, a horizontally disposed flat segmental casing 68 and a flat segmental trip member 69. Two of the casings 68 are shown, but as they are alike except being rights and lefts, the description 20 of one will suffice for both.

The casing members 68 are rigidly supported in any suitable manner and each provided with a vertical stub shaft 70 to which the segmental members 69 are attached and are movable back and forth within the casings 68. The casings 68 are each provided with an intake slot 71 in the upper face communicating with the conductor members 49 and 50, as indicated, to provide for the passage of the nails consecutively into the casings. Each of the segmental casings 68 is likewise provided with a discharge slot 72 30 communicating respectively with the chutes 43 and 44. The intake slots 71 and discharge slots 72 do not register, as indicated in Figure 15.

40 The trip plate 69 is provided with a slot 73 extending entirely therethrough; and adapted to register alternately with the slots 71 and 72.

45 Supported in any suitable manner is a rock shaft 74; and a bar 75 is slidably supported as by a guide device 76 between the lines of the casings 68.

Attached to each of the stub shafts 70 is a lever arm 77, and pivoted at their ends respectively to the lever arms 77 and the bar 50 75 are rods 78.

A spring controlled rod 79 connects the lever arms 77 and operates to hold the segmental plates 69 yieldably in position to maintain the slots 73 in registration normally with the slots 71 of the casing, as indicated in Figure 15.

Extending from the rock shaft 74 is an arm 80 pivoted at 81 to the rods 78, so that the oscillation of the rock shaft will transmit reciprocatory motion to the bar 75 and thence transmit oscillatory motion to the stub shafts 70 and vibratory motion to the plates 69, and thus cause the slot 73 to be alternately alined with the slots 71 and 72.

65 Means are provided in the modified struc-

ture for transmitting the motion of the rods 24 and 25 to the rock shaft 74, and includes arms 82 attached to the rock shaft and pivoted at 83 in longitudinally directed slots, one of which is shown at 84, in each of the rods 24 and 25, the slots 84 providing for the necessary lost motion between the movements of the plungers and the trap rods.

By this arrangement the lowermost nails in the conductors 49 and 50 will be deposited 75 by gravity in the slots 73 of the plates 69 and rest upon the lower side of the casing 68. Then as the rods 24 and 25 are moved downwardly, as described hereinbefore, the slots 84 will pass over the pivots 83 without 80 effecting the rock shaft, but at the last portion of the return stroke, the lower end of the slots will pick up the arms 82 and actuate the rock shaft and cause the plates 69 to be moved laterally and carry the nails 85 held in the slots 73 into position to be fed by gravity through the slots 72 and into the chutes 43 and 44 as in the structure shown in Figures 1 and 2, and into the paths of the plungers.

In the meantime the solid or unslotted portions of the plates 69 cut off the slots 71 and prevent the passage of the next nails from the conductors, but at the return stroke the reaction of the springs in the rod will insure the return of the plates 69 to normal position with the slots 73 again in alignment with the slot 71, or in position to receive the next nails, as will be obvious.

In Figures 17 and 18 another modification in the construction of the nail trap device is shown consisting in forming the casing 68 in semi-circular form, and increasing the throw of the plate 69 from one fourth to one half of a revolution.

The improved device can be constructed of any suitable material and adapted without material structural change to receive and drive nails of various sizes and lengths, and will drive two or more nails simultaneously.

From the foregoing it is believed that the construction, operation and advantages of the invention may be readily understood by those skilled in the art, and it is apparent that changes may be made in the details disclosed without departing from the spirit of the invention as expressed in the appended claims.

What is claimed and desired to be secured by Letters-Patent is:

1. In a nailing machine, the combination with nail driving mechanism including a cross head, of a nail box arranged at the lower end thereof, means to feed nails to said nail box including a nail trap casing horizontally arranged, a vertical stub shaft extending into the casing, the said casing having a nail intake slot through the top and a nail discharge slot through the bottom in communication with the said nail

box, the said slots extending in different directions in different locations with respect to the top and bottom of the said casing, a movable nail carrying plate within the casing attached to the said stub shaft, the said plate having a slot through it arranged to register alternately with the said slots of the casing, and means including a trap rod operated by said cross head for operating the stub shaft back and forth in the casing actuated by the said driving mechanism for operating the stub shaft to move the plate horizontally back and forth in the casing.

2. In a nailing machine, the combination with nail driving mechanism including a cross head, of a nail box arranged at the lower end thereof, means to feed nails to said nail box including a nail trap comprising a flat shallow casing horizontally disposed, a vertical stub shaft extending into the casing, the said casing having a nail intake slot through the top and a nail discharge slot through the bottom, a flat plate fitting the casing interiorly and movably and being attached to the said shaft, the said plate having a nail slot formed through it whereby when the shaft is turned the plate is moved and the slot therein brought to register with the said slots in the casing separately, and means for operating said plate including a trap rod operatively connected with said cross head.

3. In a nailing machine, the combination with nail driving mechanism including a cross head, of a nail box arranged at the lower end thereof, means to feed nails to said nail box including a nail trap comprising a flat shallow casing horizontally disposed, the said casing having sides converging, a vertical stub shaft extending into the casing near the junction of the said converging sides, a flat nail carrying plate movable in the casing, said plate having two sides convergingly arranged, said plate being connected with the said shaft near the meeting point of the said sides, said plate having a nail slot through it, the top of the said casing having a nail intake slot and the bottom of the casing having a nail discharge slot,

the said nail slot in the plate being arranged to register with the said intake and discharge slots of the casing when moved by the said shaft and at different times, and means to move said shaft including a trap rod operated by said cross head.

4. In a nailing machine, the combination with nail driving mechanism including a cross head, of a nail box arranged at the lower end thereof, means to feed nails to said nail box including a nail trap comprising a flat shallow casing horizontally disposed, the said casing having sides converging, a vertical stub shaft extending through the top into the casing near the junction of the said converging sides, the said casing having a nail intake slot through the top and a nail discharge slot through the bottom, one of the said slots being located near one of the said converging sides of the casing and the other at a distance from the said side, a flat nail carrying plate movable in the casing, said plate having two converging sides, said plate being connected with the said shaft near the junction of the said sides of the plate, the said plate having a nail slot through it arranged near one of the said converging sides of the plate, the said plate being moved by the said shaft, the nail slot of the plate being constructed to register with the said intake and discharge slots of the casing at different times, and means to move said shaft including a trap rod operated by said cross head.

5. In a device of the class described, a supporting base, guide rods extending from said base, a guide member slidably engaging said rods and spring supported thereon and provided with a guide lug, a receptacle for nails, a nail conductor leading from said receptacle, a trap device operative to intermittently feed the nails from the conductor into the path of the plunger, an operative rod for the trap device slidable through the guide lug and provided with a stop engageable with the guide lug, and a spring operating to actuate the trap operating rod.

In testimony whereof I affix my signature.
WILLIAM J. MILLER.
